[57] CLAIM

The ornamental design for men's briefs, substantially as shown and described.

DESCRIPTION

FIG. 1 is a front perspective view of men's briefs showing my new design, with the broken line matter being for the purpose of illustration only;

FIG. 2 is a rear perspective view thereof;

FIG. 3 is a front elevational view thereof;

FIG. 4 is a right side elevational view thereof, the left side being a mirror image of the right;

FIG. 5 is a rear elevational view thereof;

FIG. 6 is a top plan view thereof;

FIG. 7 is a bottom plan view thereof;

FIG. 8 is a sectional view taken along line 8—8 in FIG. 3;

FIG. 9 is a view like FIG. 1 of the briefs in an alternate position of adjustment; and

FIG. 10 is a sectional view taken along line 10—10 in FIG. 9.

Fig. 1.
